UNITED STATES PATENT OFFICE.

DAVID B. HYDE, OF SPRINGFIELD, OHIO, ASSIGNOR TO THE SAFETY EMERY WHEEL COMPANY, OF SAME PLACE.

DESIGN FOR AN EMERY-GRINDER FRAME.

SPECIFICATION forming part of Design No. 30,495, dated April 4, 1899.

Application filed March 11, 1899. Serial No. 708,781. Term of patent 7 years.

To all whom it may concern:

Be it known that I, DAVID B. HYDE, a citizen of the United States, residing at Springfield, in the county of Clark and State of Ohio, have invented and produced a new and original Design for an Emery-Grinder Frame, of which the following is a specification.

In the accompanying drawings, which form part of this specification, Figure 1 is a perspective view of a grinder-frame, showing my new design. Fig. 2 is a vertical cross-sectional view taken through the center of the frame.

As shown in the drawings, the leading or material feature of my new and original design consists in having the upper part A of the frame constructed substantially diamond shape and mounted on a base or pedestal B, as shown and hereinafter more fully identified. This diamond-shaped upper part is provided at or near its center with a sleeve-like portion a , which extends lengthwise therewith from each end toward the center and joins a square-shaped opening a' in the cen-

ter of the frame, as shown. The outer edge 25 of the diamond-shaped frame is provided with broad flanges or ribs a^2 , and the lower part of the frame proper recedes longitudinally and extends laterally until it assumes a square shape, as shown at a^3 , where it joins 30 the pedestal or lower portion B. The base or pedestal B on which this diamond-shaped upper part is supported is constructed on the order of a truncated pyramid, which at the bottom extends laterally into flanges b' to 35 form a supporting-base, the whole forming a pleasing outline, as shown.

Having described my invention, what I claim as new, and desire to secure by Letters Patent, is—

40

The design for an emery-grinder frame substantially as herein shown and described.

In testimony whereof I have hereunto set my hand this 3d day of March, A. D. 1899.

DAVID B. HYDE.
